(57) **CLAIM**

The ornamental design for a headphone positioning device, as shown and described.

DESCRIPTION

FIG. 1 is a perspective view of most of the front surface, top surface, and left surface of a headphone positioning device in accordance with the present design;

FIG. 2 is another perspective view thereof;

FIG. 3 is another perspective view thereof;

FIG. 4 is a left side view thereof;

FIG. 5 is a right side view thereof;

FIG. 6 is a bottom side view thereof;

FIG. 7 is a top side view thereof;

FIG. 8 is a front side view thereof;

FIG. 9 is a back side view thereof, the front side view being a mirror image of the back side view; and,

FIG. 10 is a front side view of the headphone positioning device in use with a headphone and cable assembly, the broken line showing a headphone and cable is for illustrative purposes only and forms no part of the claimed design.

FIG. 11 is a front side view of the headphone positioning device and showing a headphone and cable, the broken line showing the headphone and cable is shown for illustrative purposes only and forms no part of the claimed design.

FIG. 12 is a front side view of the headphone positioning device in use with a headphone and cable assembly, the broken line showing the headphone and cable is shown for illustrative purposes only and forms no part of the claimed design; and,

FIG. 13 is a perspective view of the headphone positioning device in use with a headphone and cable assembly shown as the device would be worn by a person in and around the ear, the broken line showing the headphone, headphone cable, and ear is for illustrative purposes only and forms no part of the claimed design.
